FLEXIBLE DRIVE SHAFT FOR MANICURING TOOLS AND THE LIKE

James W. Bradbury, Middletown, Ohio, assignor to Forward Corporation, West Middletown, Ohio, a corporation of Ohio

Filed May 24, 1962, Ser. No. 70,264

Term of patent 14 years

(Cl. D55—1)

FIG. 1 is a side elevational view of a flexible drive shaft for manicuring tools and the like, showing my new design broken away to indicate intermediate length;

FIG. 2 is a plan view taken from the left of FIG. 1; and FIG. 3 is a plan view taken from the right of FIG. 1.

I claim:

The ornamental design for a flexible drive shaft for manicuring tools and the like, as shown and described.
